UNITED STATES PATENT OFFICE.

CYRUS DOLPH, OF PRESTON, ONTARIO, CANADA.

BARN.

1,079,040.

Specification of Letters Patent.

Patented Nov. 18, 1913.

Application filed January 21, 1913. Serial No. 743,400.

To all whom it may concern:

Be it known that I, CYRUS DOLPH, a subject of the King of Great Britain, residing at Preston, in the county of Waterloo and 5 Province of Ontario, Canada, have invented a new and useful Barn, of which the following is a specification.

The invention relates to improvements in barns.

10 The object of the present invention is to improve the construction of barns, more especially that shown and described in an application filed by me Oct. 26, 1912, Serial No. 727,905, and to provide a barn frame of 15 simple, strong and inexpensive construction, which will be easy to erect and afford a maximum amount of space for the storage of the contents of the barn.

It is also the object of the invention to 20 provide a barn frame in which cross beams will be eliminated and in which the roof will be supported at the hips without obstructing the interior, thereby permitting the use of slings for lifting great quantities of hay and 25 grain and enabling a maximum amount of such material to be handled in the busy season.

Another object of the invention is to enable 30 the entire side of the barn frame to be put together on the ground and pulled into position by blocks and tackle, thereby permitting most of the work to be done on the ground where the work can be performed with greater rapidity than is possible when 35 a barn frame is built up from the ground in the ordinary manner.

With these and other objects in view, the 40 invention consists in the construction and novel combination of parts hereinafter fully described, illustrated in the accompanying drawings, and pointed out in the claims hereto appended; it being understood that various changes in the form, proportion, size 45 and minor details of construction, within the scope of the claims, may be resorted to without departing from the spirit or sacrificing any of the advantages of the invention.

In the drawings: Figure 1 is a transverse 50 sectional view of a barn, constructed in accordance with this invention. Fig. 2 is a central longitudinal sectional view of a portion of the same. Fig. 3 is an enlarged perspective view of a portion of the barn frame, illustrating the construction of one 55 of the side trusses. Fig. 4 is a detail per-

spective view of one of the purlin plates. Fig. 5 is a transverse sectional view of one side of a barn frame, illustrating another form of side truss. Fig. 6 is a detail perspective view, illustrating the manner of mounting an attaching plate without kerfing a timber.

Like numerals of reference designate corresponding parts in all the figures of the 65 drawings.

In the accompanying drawings in which is illustrated the preferred embodiment of the invention, the frame of the barn is supported upon a suitable foundation 1, which 70 receives side and end sills 2 and 3 and which also supports the terminals of cross sills 4. Mounted upon the sills 2 are vertical side posts 5, arranged at the corners of the barn frame and at intervals throughout the 75 length of the same and connected at their upper ends by wall plates 6, which support the rafters of the barn. The side posts are shown built up of a plurality of separate planks or pieces, but they may consist of a 80 solid timber and any of the sills may be either constructed solid or built up to the side posts. The wall plates 6 also preferably consist of two or more planks or pieces fitted flat against each other to provide a 85 plate of a strength corresponding to the size of the barn.

The rafters are composed of upper and lower sections 7 and 8, arranged at a slight angle to each other and connected at their adjacent ends by side timbers or purlins 9, preferably made up of a plurality of separate planks or pieces, as shown, and fitted in recesses 10 and 11 of the adjacent ends of the upper and lower sections of the rafters. 95 The lower sections 8, which are provided at their lower ends with recesses 12 to fit the wall plates 6, are preferably arranged at an angle of approximately fifty-six degrees, and the upper rafter section 7 is arranged at 100 an angle of approximately thirty-four degrees. The upper and lower rafter sections are of the same length and have the same width and the tendency of the lower rafter sections to fall inwardly is just overcome by 105 the inclination of the upper rafter sections to settle at the ridge of the roof and spread at their heels. These forces being equalized, anything which adds strength to the joint tends to strengthen the entire roof structure, 110 while the form is such as to throw considerable of a vertical load on the wall plates and

lessen the heavy outward thrust incident to most of the forms of barn roofs in use.

The upper ends of the upper sections of the rafters are connected to form a ridge 5 by transverse plates 13, constructed of steel or other suitable material and adapted to be employed for hanging a hay carrier track or other means for handling the contents of the barn. The wall plates 6 are supported between the side posts by studs 14 and oppositely inclined braces 15 mounted upon the side sills. The studs are located centrally of the space between the side posts, and the braces, which are oppositely inclined, extend upwardly from the lower ends of the side posts to the upper ends of the studs. Any other suitable arrangement of the braces and studding may, of course, be employed.

The barn frame is provided at its ends 20 with vertical posts or uprights 16, located in spaced relation with the corner posts and extending above the plane of the wall plates and having their ends fitted under the ends of the purlin 9 and supporting and suitably secured to the same. The end posts 16 are connected at a point intermediate of their ends by a central horizontal end beam 17, preferably composed of two planks or pieces, located in the horizontal plane of the wall 25 plate 6 and supported at the center by a vertical stud 18 and oppositely inclined braces 19. The end posts 16 are also connected with the corner posts by side and end beams 17^a, composed of two planks or pieces 30 and arranged in the plane of the central end beam 17. The barn frame is provided at the gables with a central vertical stud 20 and inclined braces 21, arranged upon the horizontal beam 17. The vertical stud 20 is 35 preferably composed of two planks or pieces, and the braces 21 preferably extend upwardly and outwardly from the lower end of the central stud 20 to the upper ends of the posts 16. The studs and the inclined braces 40 besides strengthening the framework of the barn prevent the sides and ends of the same from getting out of plumb. The ends of the barn are also braced and prevented from bulging under the internal pressure of its 45 contents by diagonal corner braces 22 and by the end tie rod shown and described in the aforesaid application.

Long inclined tie rods 25 extend downwardly and outwardly from the upper ends 50 of the end posts 16 to the wall plates 6 at points intermediate of the ends thereof. The long inclined longitudinally disposed tie rods 25 at opposite ends of the barn operate against each other, as set forth in the aforesaid application in such a manner as to prevent wind pressure from forcing the roof out of place and at the same time they help materially to hold the side plates from bulging.

65 The barn frame is equipped at each of the

side posts with an upright interior truss, constructed of structural steel, or other suitable material, either wood or metal, and comprising a main upwardly and inwardly inclined truss member 26, extending from the lower end of the side post 5 to the purlin 9 and composed of spaced angle bars, or other suitable material and secured at its lower end to the cross sill 4 and side post 5 by a vertical plate 27, constructed of steel or other suitable material and having its lower portion secured in a kerf 28 in the cross sill 4 and between the planks of the side post 5 by transverse bolts 29. The upper portion of the plate 27 extends between the angle bars of the main truss member 26, and is riveted or otherwise secured to the parallel sides or wings thereof. The upper end of the main truss member is connected with the purlin 9 by a purlin plate 30, riveted or otherwise secured between the parallel sides or wings of the angle bars of the main truss member and constructed of steel or other suitable material, and provided at the top with oppositely disposed horizontal flanges 31, 90 which are secured by bolts or other suitable fastening devices to the underside of the purlin 9. The upper portion of the purlin plate is split at the center, and the partially severed portions are bent in opposite directions to form the said flanges 31, the lower portion of the purlin plate constituting a depending attaching web, which extends between the angle bars of the main truss member. 95

The main truss member is supported by a lower inclined brace 32, arranged at an angle to the lower portion of the main truss member at the inner side thereof and preferably composed of spaced angle bars and extending upwardly and outwardly from the cross sill 4 to the intermediate portion of the main truss member and connected with the same at a point slightly below the horizontal plane of the wall plate 6. The lower end of the inclined brace 32 is secured to the cross sill 4 by an inner lower attaching plate 33, constructed of steel or other suitable material and secured in a vertical kerf 34 of the cross sill by transverse bolts 35, or other suitable fastening devices, and having a tapered upper portion extending between the lower ends of the spaced angle bars of the said inclined brace 32 and riveted or otherwise secured to the same. The upper end of the inclined brace is connected with the main truss member by an inner intermediate attaching plate 36, also constructed of steel or other suitable material and riveted or otherwise secured in the space between the angle bars or members of the main truss member and projecting inwardly and outwardly from the same, the inwardly projecting portion being riveted or otherwise secured between the upper ends of the an- 100 105 110 115 120 125 130

gle bars of the lower inclined brace 32. The outwardly projecting portion of the inner intermediate attaching plate 36 is secured between spaced angle bars of a strut 37, extending from the main truss member to the upper end of the side post 5 and connected with the latter by an outer intermediate attaching plate 38. The outer intermediate attaching plate 38, which is secured between the planks of the side post 5 by transverse bolts 39, projects inwardly from the upper end of the side post and extends into the space between the angle bars of the strut, and is riveted or otherwise secured to the same. The inwardly projecting portion of the outer intermediate attaching plate also extends between the lower ends of spaced angle bars of an upper inclined brace 40, and is riveted or otherwise secured to the same. The upper inclined brace 40, which is arranged at an angle to the upper portion of the main truss member, extends upwardly and inwardly from the upper end of the side post to the purlin 9 and is connected with the same by the purlin plate 30, which is riveted or otherwise secured between the upper ends of the angle bars of the upper inclined brace 40. Instead of kerfing the timbers of the barn frame to secure the attaching plates to the same, the attaching plates may be mounted between spaced wings or flanges 41 of angle bars 42, as shown at 43 in Fig. 6 of the drawings. The angle bars 42, which may be of any length, have their wings or flanges perforated for the reception of bolts or other suitable fastening devices, and they may be applied to the timbers of any portion of the barn frame and can be substituted for such timbers.

In Fig. 5 of the drawings is illustrated another form of side truss comprising a main truss member 44, arranged at an inclination and extending upwardly and inwardly from the lower end of the corner post 5 to the purlin and supported by an inner inclined brace 45. The main truss member, which is composed of spaced angle bars, is connected at its lower end with the cross sill 4 and the side post 5 by a lower outer attaching plate 46, and its upper end is connected with a purlin 9 by a purlin plate 47, the plates 46 and 47 being constructed similar to the plates 27 and 30 heretofore described. The inclined brace, which is composed of spaced angle bars, is connected at its lower end with the cross sill by an inner lower attaching plate 48, and it is secured at its upper end to an intermediate attaching plate 49. The intermediate attaching plate 49, which is mounted between the spaced angle bars of the main truss member, extends inwardly and outwardly therefrom and its inwardly extending portion is secured between the upper ends of the angle

bars of the lower inclined brace. The outwardly extending portion of the intermediate attaching plate 49 is secured to the lower end of a short intermediate inclined brace 50, composed of spaced angle bars and extending upwardly and outwardly from the upper end of the lower inclined brace 46 to the upper end of the side post 5 to which it is connected by an outer intermediate attaching plate 51. The intermediate attaching plates extend between the angle bars of the intermediate inclined brace, and the outer intermediate attaching plate is also riveted or otherwise secured between the lower ends of the spaced angle bars of an upper inclined brace 52, extending from the upper end of the side post to the purlin 9 and connected with the same by the purlin plate 47, which has its depending web secured between the upper ends of the angle bars of the upper inclined brace 52. The outer intermediate attaching plate 51 is connected with the main truss member by a horizontal strut 53, composed of spaced angle bars secured at their outer ends to the plate 51 and extending between the upper ends of the intermediate inclined brace 50 and the lower end of the upper inclined brace 52. The horizontal strut 53 is equipped at its inner end with an attaching plate 54, which is secured between the angle bars of the strut and the main truss member.

The side trusses, which brace the barn at the side posts, take up but a small amount of space and are practically out of the way, the strain being equalized by certain of the truss members in tension and others in compression, and when subjected to external pressure, the members of the truss, which are subjected to a compressing strain under internal pressure, are placed under tension, and those which are subjected to tensile strain from interior pressure are subjected to compression from external pressure. The construction and arrangement of the side trusses is such to adapt them to resist internal pressure from the contents of the barn and external wind pressure, and they provide a rigid structure under both conditions.

As explained in the aforesaid application, the barn is designed to be covered with either wood or corrugated metal, or other suitable material (not shown) laid on and secured to the bars 55. The floor 56 is laid on joists 57, and the barn is designed to be provided with suitable door openings (not shown), which may be located at either the sides or ends of the barn.

What is claimed is:

1. A structure of the class described including a post, a rafter composed of upper and lower angularly related sections, and a purlin connected with the adjacent ends of the rafter sections, and a truss comprising a main inclined truss member extending

from the lower end of the post to the purlin, a lower inclined brace extending upwardly and outwardly and connected at its upper end to the main truss member at a point intermediate of the ends thereof, a strut connected with the main truss member at a point intermediate of the ends thereof and extending therefrom to the upper end of the post, and an upper inwardly inclined brace 10 connected with the outer end of the strut and extending from the same and connected with the upper end of the main truss member at the purlin.

2. A structure of the class described including a post, inclined roof supporting means, and a truss comprising a main inclined truss member extending from the lower end of the post to a point intermediate of the ends of the inclined roof supporting means, a lower brace located at the inner side of the main truss member and connected at its upper end with the same, a strut connected with the main truss member at a point intermediate of the ends thereof and extending to the said post, an upper inclined brace extending upwardly from the post and connected at its upper end with the main truss member at the said roof supporting means, and means for connecting 30 the strut and the upper brace with the said post.

3. A structure of the class described including a side post, a rafter composed of upper and lower angularly related sections, and a purlin connected with the adjacent ends of the rafter sections, and a side truss comprising a main inclined truss member extending from the lower end of the side post to the purlin, an attaching plate secured to the main truss member at a point intermediate of the ends thereof and projecting inwardly and outwardly therefrom, a lower inclined brace secured at its upper end to the inner portion of the attaching 40 plate and secured at its lower end in spaced relation with the lower end of the main truss member, an inclined bar secured to the outer portion of the said attaching plate and connected with the side post at the upper 45 end thereof, and an upper inclined brace connected at its lower end with the upper ends of the side post and the said inclined bar and extending therefrom to the upper end of the main truss member and connected 50 therewith at the purlin.

4. A structure of the class described including a side post, a rafter composed of upper and lower angularly related sections, and a purlin connected with the adjacent 60 ends of the rafter sections, and a side truss comprising a main inclined truss member extending from the lower end of the side post to the purlin, a pendent purlin plate secured to the upper end of the main truss member and provided at the top with

flanges extending in opposite directions and secured to the purlin, a lower inclined brace arranged at the inner side of the main truss member and connected at its upper end to the same at a point intermediate of the 70 ends of the main truss member, an upper inclined brace extending from the upper end of the side post to the purlin plate and secured to the same, and a strut connected with the main truss member at a point intermediate of the ends thereof and extending outwardly from the same and connected with the upper end of the side post and with the lower end of the upper inclined brace. 75

5. A structure of the class described including a sill, a side post, a rafter composed of upper and lower angularly related sections, and a purlin connected with the adjacent ends of the rafter sections, and a side truss comprising inner and outer lower attaching plates spaced apart and secured to the said sill, the outer attaching plate being located at the lower end of the side post, a purlin plate secured to the purlin, a main truss member extending from the outer 80 lower attaching plate and secured to the same, an inner inclined brace secured at its lower end to the lower inner attaching plate and connected at its upper end to the main truss member at a point intermediate of the 85 ends thereof, an upper inclined brace extending from the upper end of the side post to the purlin plate and connected therewith, and a strut extending outwardly from the main truss member at a point intermediate of the 90 ends thereof and connected with the lower end of the upper inclined brace and with the upper end of the side post. 95

6. A structure of the class described including a post, a rafter composed of upper and lower angularly related sections, a purlin connected with the adjacent ends of the rafter sections, a pendent purlin plate secured to the purlin, a main inclined truss member extending from the lower end of the post to the purlin plate and secured to the same, a lower brace located at the inner side of the main truss member and connected at its upper end to the same at a point intermediate of the ends thereof, an upper brace 105 connected with the post and extending upwardly therefrom to the said purlin plate and secured to the latter, and a strut extending from the main truss member to the post and connected with the said parts. 110

7. A barn frame of the class described including a side post, and inclined roof supporting means, and a side truss comprising a main inclined truss member extending from the lower end of the side post and connected with the barn frame at a point intermediate of the ends of the roof supporting means, a lower inclined brace arranged at the inner side of the main truss member and connected at its upper end to the same 125 130

at a point intermediate of the ends thereof, an upper inclined brace arranged at an angle to the upper portion of the main truss member and extending from the upper end of the 5 side post and connected at its upper end to the upper end of the main truss member, and a bar extending outwardly from the main truss member at a point intermediate of the 10 ends thereof and connected with the lower end of the upper inclined brace and with the said post.

8. A barn frame of the class described including a side post, and inclined roof supporting means, and a side truss comprising 15 a main inclined truss member extending from the lower end of the side post and connected with the barn frame at a point intermediate of the ends of the roof supporting means, a lower inclined brace arranged at 20 the inner side of the main truss member and connected at its upper end to the same at a point intermediate of the ends thereof, an upper inclined brace arranged at an angle 25 to the upper portion of the main truss member and extending from the upper end of the side post and connected at its upper end to the upper end of the main truss member, and an inclined strut arranged at an angle to the 30 upper and lower inclined braces and extending outwardly from the main truss member

at the upper end of the lower inclined brace and connected with the lower end of the upper inclined brace and with the said post.

9. A barn frame of the class described including a side post, and inclined roof supporting means, and a side truss comprising 35 a main inclined truss member extending upwardly and inwardly from the barn frame adjacent to the horizontal plane of the lower ends of the side post and connected at its 40 upper end to the barn frame at a point intermediate of the ends of the roof supporting means, a lower inclined brace arranged at an angle to the lower portion of the main truss member and connected at its upper end to the said member, and means for connecting the lower end of the upper inclined 45 brace with the main truss member and with the upper end of the lower inclined brace and the said post.

In testimony, that I claim the foregoing as my own, I have hereto affixed my signature in the presence of two witnesses.

CYRUS DOLPH.
